Design for Saws.

Edwin Moore

United States Patent Office.

EDWIN MOORE, OF BROOKLYN, E. D., N. Y., ASSIGNOR TO THE BISSELL AND MOORE MANUFACTURING COMPANY, OF NEW YORK CITY.

Design No. 3,994, dated April 26, 1870.

DESIGN FOR THE SHAPE OF THE SLOTS BETWEEN SAW-TEETH.

The Schedule referred to in these Letters Patent and making part of the same.

To all whom it may concern:

Be it known that I, EDWIN MOORE, of Brooklyn, E. D., in the county of Kings and State of New York, have invented or produced a new and original Design for the Shape and Configuration of the Slots between the Teeth of Saws; and the following is declared to be a correct description thereof, reference being had to the drawing, which represents a portion of a saw with large-sized teeth.

The object of this configuration is to give strength to the respective teeth at the base, and prevent sawdust adhering in the slot.

The scoring-teeth *a a* are sharpened and set, and stand in groups, as heretofore usual, and the clearing-teeth *b b* stand back to back, and are sharpened like chisels, as has heretofore been done.

My invention relates to the shape and configuration of the slot or notch between the teeth *a* and *b*.

Commencing at the point of the tooth *b*, the edge

of the slot runs into the saw-blade nearly at right angles to the length of the saw, as at the side 2.

The bottom of the slot is nearly a semicircle, as at 3, so that there is not any angle for sawdust to adhere by becoming wedged.

The metal of the saw between the teeth *a* and semicircle 3 is left with a fullness, as at 4, so that the base or bank of the teeth *a a* will be as strong as possible, to prevent the base of the group of teeth being bent while in use.

I claim as my invention—

The shape and configuration of the slot between the teeth *a* and *b*, as shown.

Dated February 7th, 1870.

EDWIN MOORE.
